PENCIL

Harold H. Belcher, Philadelphia, Pa.

Application February 17, 1934, Serial No. 711,804

12 Claims. (Cl. 120—18)

This invention relates to improvements in writing pencils, and more specifically in mechanical pencils of the type comprising a holder having mechanical means for extending the lead or crayon as the latter is worn away in the writing operation.

A principal object of the invention is to provide in a pencil of this character means automatically operative in the normal writing operation for 10 rotating the lead or crayon with respect to that portion of the holder held in the hand to thereby avoid undue flattening of the writing point and to insure substantial uniformity in the written lines or markings.

15 The invention further resides in certain mechanical details and arrangements hereinafter set forth and illustrated in the attached drawings, in which:

Figure 1 is a fragmentary longitudinal sectional view of a pencil made in accordance with 20 my invention;

Fig. 2 is a transverse sectional view on the line 2—2, Fig. 1;

Fig. 3 is a longitudinal sectional view on the 25 line 3—3, Fig. 2;

Figs. 4, 5, and 6 are detached views in perspective of elements of the mechanism;

Fig. 7 is a fragmentary view in perspective of 30 one end of the casing element shown in Fig. 4;

Fig. 8 is a sectional view on the line 8—8, Fig. 35 1;

Fig. 9 is a longitudinal sectional view corresponding to that of Fig. 1 illustrating the mode of 40 operation;

Figs. 10 and 11 are diagrammatic transverse sectional views enlarged, also illustrative of the 45 mode of operation;

Fig. 12 is a fragmentary longitudinal sectional view illustrating the means for longitudinally 50 feeding the lead or crayon in the holder;

Figs. 13, 14, and 15 are views in perspective showing details of the feeding mechanism;

Fig. 16 is a fragmentary longitudinal sectional view illustrating a modification within the scope 55 of the invention;

Fig. 17 is a transverse sectional view on the line 17—17, Fig. 16, and

Fig. 18 is a fragmentary longitudinal sectional view illustrating a still further modification.

50 With reference to the drawings, a pencil made in accordance with my invention may comprise an outer or main casing 1 and an interior casing 2 suitably fixed within the barrel of the main casing. In the present instance, the casing element 2, shown in perspective in Fig. 4, is made

of resilient metal and has at its upper end an integral turned over spring extension 3. At the opposite end, the casing element 2 has a terminal section 4 of reduced diameter which loosely embraces the lower end of a sleeve 5, and this sleeve, 5 as illustrated in Figs. 1 and 5, has adjacent its lower end a transversely projecting pin 6 which enters an aperture 7 in the reduced end portion 4 of the casing 2 and thereby anchors the sleeve 5 to the casing. As shown in Fig. 7, the aperture 10 10 7 is formed in a tongue 8 formed in the end portion 4 of the casing element 2 by a pair of recesses 9, 9 extending inwardly from the edge of the latter. This tongue 8, constituting an integral part of the casing element 2, is resilient 15 and permits the sleeve 5 to rock within the casing element 2. As shown in Fig. 5, the sleeve 5 is provided at its lower end with a series of teeth 11, the function of which will be described, herein- 20 after.

Rotatably fitted within the sleeve 5 is a tubular element 12 having a spiral slot 13 in the wall thereof, and this element 12 is supported on the upper end of the sleeve 5 by a collar 14 secured to the outside of the tubular element. Rotatably 25 mounted within the tubular element 12 is a hollow stem 15 which carries at its lower end a conical tip 16, the upper enlarged end of which engages the lower end of the tubular element 12. The stem 15 is held against longitudinal movement in the tubular element 12 by a clip 20, see Fig. 8, which is fastened in the tubular element 12 and which enters a circumferential recess 17 at the upper end of the stem 15, this anchoring means permitting rotation of the stem 15 in the 30 tubular member. 35

As shown in Fig. 12, a central bore extends completely through the stem 15 and the tip 16, and in this bore is slidably mounted a plunger 18 having at its upper end transversely projecting ears 19, 19^a which pass through a longitudinal slot 21 in the stem 15 and enter the spiral groove 13 of the tubular element 12. The arrangement is such that relative rotation of the tubular element 12 and the stem 15 effects a longitudinal movement within the stem of the plunger 18. As illustrated in Figs. 12 to 15, the plunger 18 comprises two parts, an outer tubular element 22 and an inner plunger element 23, the latter having limited sliding movement within the tube 22. The projection 19 previously mentioned extends from the tube 22, while the other projection, 19^a, extends from the plunger 23 and projects through a slot 24 in the side of the tube 22. The lower end of the tube 22 is split longitudinally 55

and is adapted to receive and to frictionally retain the inner end of a piece of lead or crayon shown at 25 in Fig. 12. The lead is inserted in the lower end of the tube 22 through the outer 5 end of the tapered head 16. With this arrangement, the lead may be either extended from or retracted into the head portion 16, depending on the direction of the relative movement of the stem 15 and the tubular member 12. When, however, the plunger 18 is advanced to the point where the projection 19 of the tube 22 reaches the lower end of the spiral groove 13, further 10 relative rotational movement of the stem 15 and the tubular element 12 will cause an additional 15 advance movement of the plunger element 23, expelling the lead 25 from the end of the tube 22. This mechanism for longitudinally feeding the lead in the pencil is well known in the art and forms only an incidental part of the present 20 invention.

It will be apparent that when the parts of the mechanism described above are in the relative positions shown in Fig. 1, the tubular element 12 may rotate freely within the sleeve 5 and with 25 respect to the casing elements 1 and 2, and hence rotation of the tip with respect to the casing will have no feeding effect upon the lead, since it involves no relative movement between the tubular element 12 and the spindle 15. At the inner end 30 of the conical head portion 16, the tubular element 12 carries a projecting lug or tooth 26 which, when the tubular element 12 is moved inwardly from the position in which it is shown in Figs. 1 and 2, engages in the spaces between the teeth 35 11 on the outer end of the sleeve 5, see Fig. 12. When thus engaged, the tubular element 12 is locked against rotation with respect to the sleeve 5, and the sleeve 5 as previously set forth is anchored against rotational movement in the inner 40 casing member 2. Rotation of the conical head portion 16 with respect to the casing 1, under these conditions, results in the aforesaid relative rotation of the stem 15 secured to the head 16 and the tubular element 12, with a consequent 45 advance or retraction of the plunger 18 and of the lead or crayon 25, as previously set forth.

The element 12 is held resiliently in a normal position, as shown in Fig. 9, by the spring extension 3 of the inner casing 2, the back-turned 50 terminal end of which is apertured at 27 for reception of a pin 28 which projects from a cylinder 29 fitted into the upper end of the said tubular element. The member 29, see Fig. 6, has a depending bracket arm 31, the offset end of which 55 is apertured at 32 for reception of a pin 33 secured to the inner casing member 2 and projecting beyond the upper end of the latter. This pin 33 constitutes a pivot about which the upper end of the cylindrical member 29 may rock. The 60 spring extension 3 of the inner casing 2 not only resiliently retains the tubular element 12 in the normal relatively inclined position, but also permits the rocking movement of the upper end of the element upon the pin 33. The resiliency of 65 the spring 3 also permits movement of the cylindrical member 12 longitudinally into the position, as shown in Fig. 12, in which the lug 26 engages between the teeth 11 of the sleeve 5.

Pivotedly mounted in the inner end of the cylinder 29 is a pawl 34, the free end of which is resiliently held in contact with the inner surface of the tubular element 12 by means of a spring 70 35 also mounted in the inner end of the cylinder 29. The normal position of the pawl 34 with respect to the cylindrical member 12 is clearly

shown in Fig. 11. Assuming now that pressure is applied as in the normal act of writing upon the terminal end of the tip 16 tending to displace this element transversely with respect to the casing 1 held in the hand of the writer and that this pressure is sufficient to actually cause a displacement of the head element 16 with respect to the casing 1 and a resultant rocking of the cylindrical member 12 in the casing about the fulcrum formed by the reduced lower end portion 10 of the inner casing 2, it will be apparent that the lateral displacement of the upper end of the tubular element 12 about the pin 33 and against the tension of the spring 3 will necessarily cause a relative rotational movement between the cylinder 29 and the element 12 in which the cylinder is seated. This will be clear from Figs. 9, 10, and 11, wherein the tubular element 12 is shown in full lines occupying its normal position within the casing and resiliently held by the spring 3. 20 As pressure is applied to the extremity of the tip 16 shifting the latter and the element 12 to the dotted line positions, it will be apparent that in this movement, due to the fact that the cylinder 29 in the upper end of the tubular element 25 12 is constrained to move about the pivot pin 33, there will be a movement of the cylinder 29 within the element 12 in the direction of the arrow, see Fig. 11. This relative movement of the cylinder 29 and the element 12 is not restrained 30 by the pawl 34, but when the pressure is relieved from the head 16 and the spring 3 is permitted to return to the parts to the normal full line position, the pawl 34 will grip the cylindrical member 12 and will effect a rotation of this member 35 and of the associated parts including the elements which hold the lead in a clockwise direction, see Fig. 11, and there will be a consequent partial rotation of the lead with respect to the casing 1. Each subsequent displacement of the parts with 40 respect to the casing 1, as previously set forth, results in a further rotative movement of the lead so that the normal act of writing is accompanied by an intermittent rotation of the lead 45 with respect to the casing.

With this arrangement, it is desirable, for maximum operating efficiency, to hold the casing 1 in such position in the hand that the pressure exerted on the tip 16 will be in the direction best adapted to effect the movement of the parts about the controlling pivot 33, and to this end I prefer to provide the pencil with suitable markings indicating the position in which it should be held in the hand of the writer. It will be understood that while the element 12 may be moved 55 against the tension of the spring 3 to bring the lug 26 into interlocking engagement with the teeth 11 on the sleeve 5, the pressure required for this longitudinal adjustment of the element 12 is considerably greater than that required for the rocking motion of the element for the purpose of rotating the lead.

In Figs. 16 and 17, I have illustrated a modification in which rotation of the lead-holding elements is effected by longitudinal movement of the tip element 16a with respect to the casing 1a. In this case, the tip 16a and the cylindrical member 12a are held in an extended position by a coiled spring 36 which is confined between the 70 collar 14a secured to the cylindrical member 12a and a spring retainer 37 secured in the inner casing 2a, which element 37 also constitutes a guide in which the cylindrical member 12a is slideable and which normally retains the casing 12a con- 75

centrically positioned within the casing. In this instance, the upper end of the cylindrical member is provided with a ratchet wheel 38, the teeth of which are engaged by a spring-pressed pawl 39 pivotally mounted, as shown in Fig. 17, in the inner casing 2a. Normally the pawl 39 under pressure of a spring 41 occupies a downwardly inclined position in engagement with the ratchet 38. Pressure applied to the tip 16a in a normal writing operation tends to displace the tip inwardly in the casing 1a, thereby effecting a longitudinal adjustment of the cylindrical member 12a in the casing and an elevation of the pawl 39 about its pivot. Since the ratchet 38 is held against lateral displacement in the casing, this upward adjustment of the pawl 39 in engagement with the teeth of the ratchet wheel effects a rotation of the latter and consequently of the lead-holding elements. When the pressure is released, the springs 36 and 41 return the parts to their normal relative positions. Each subsequent longitudinal movement of the cylindrical member 12a in the casing results in an additional rotational movement of the lead.

In both of the aforescribed embodiments, it will be noted that the rotation of the lead-holding means and therewith of the lead is effected by the bodily displacement of said means in the casing resulting from a normal writing operation. In the embodiment of Figs. 1 to 12, the bodily displacement of the holding means effecting rotation thereof is independent of and distinct from the longitudinal adjustment of the holding means required to feed the lead longitudinally; while in the embodiment of Figs. 16 and 17, the bodily displacement of the holding means which effects rotation of the lead corresponds to the longitudinal adjustment of the holding means required to longitudinally feed the lead, but is of lesser amplitude.

A still further embodiment of the invention is shown in Fig. 18, wherein the ratchet wheel 38a on the inner end of the cylindrical member 12b is engaged by a pawl 39a, which in this instance is pivotally connected to the short end of a lever arm 42 pivotally mounted at 43 in the casing. The opposite end of this lever arm 42 carries a weight 44, movement of which is controlled by a light spring 45 which tends to hold the weighted lever 41 in a predetermined normal position, as illustrated. In this instance, the cylindrical member 12b is fixed against longitudinal movement in the casing but is free to rotate. Movement of the pencil in the normal writing operation causes a reciprocation of the weighted lever 42 and a resulting action of the pawl 39a upon the ratchet wheel 38a effecting an intermittent rotation of the latter and of the lead-holding elements associated therewith.

It will be apparent that there may be other modifications without departure from the invention.

I claim:

1. A writing pencil comprising a casing, a marking element supported in the casing, and having an exposed portion constituting the pencil "point", and mechanism operative by intermittent pressure applied to said point for revolving said element with respect to the casing.

2. A writing pencil comprising a casing, means in the casing for holding a marking element with one end exposed to form the pencil "point", and mechanism operative by intermittent unbalanced and non-rotative pressure exerted on the holding

means through said "point" for revolving said holding means in respect to the casing.

3. A writing pencil comprising a casing, means in the casing for holding a marking element, and mechanism operative automatically by manipulation of the pencil in the writing operation for revolving said holding means with respect to the casing. 5

4. A writing pencil comprising a casing adapted for reception of a marking element, and means 10 operative by the forces and pressures incident to the writing operation for rotating the said element in the casing.

5. A writing pencil comprising a casing, means 15 rotatably mounted in the casing for holding a marking element, and means actuated by the intermittent pressures applied to said element during the writing operation for rotating said holding means in the casing.

6. A writing pencil comprising an outer casing, 20 means rotatably mounted in the casing for holding a marking element, and mechanism operatively associated with said holding means and including a ratchet device automatically operative during the writing operation for rotating the said 25 holding means in the casing.

7. A writing pencil including a casing, means 30 in said casing for holding a marking element, said holding means being both rotationally and bodily movable with respect to the casing, and means actuated by said holding means when the latter is bodily moved for rotating said holding means in the casing.

8. A writing pencil comprising a casing, means 35 in said casing for holding a writing element, said holding means being rotatable in the casing and being bodily movable in the casing by pressure applied to the writing element, and mechanism actuated by the holding means when the latter is bodily moved for rotating the holding means in 40 the casing.

9. A writing pencil comprising a casing, means 45 in said casing for holding a marking element, said holding means being rotatable and being mounted for bodily movement in the casing, means for resiliently retaining said holding means in a normal position of bodily adjustment, said holding means being bodily movable from said normal position by pressure applied to the marking element, and mechanism actuated by the holding means when the latter is bodily moved for rotating the holding means in 50 the casing.

10. A writing pencil comprising a casing, means 55 in said casing for holding a marking element, said holding means being rotatable and being mounted for bodily movement within the casing, means for resiliently supporting said holding means in a normal position of bodily adjustment, ratchet mechanism operatively associated with said holding means and with the casing, and means operative by the holding means in its bodily movement for actuating the ratchet mechanism to rotate the holding means in the casing. 60

11. A writing pencil comprising an outer tubular casing, an inner tubular member mounted 65 both for rotation and bodily movement in the casing, a longitudinally channeled stem mounted for rotation within said tubular member but fixed longitudinally in the latter, said stem having a portion projecting from an end of the said member and from the casing and being adapted for reception of a marking element, a plunger slidably mounted in said stem for feeding engagement with said element and having a part projecting into a spiral groove in the tubular mem- 70 ber. 75

- ber whereby relative rotation of the stem and said member effects a longitudinal adjustment of the plunger in the stem, means actuated by longitudinal adjustment of the tubular member in the casing for immobilizing the said member rotationally with respect to the casing, resilient means opposing said adjustment and resiliently retaining the tubular member in a normal position of bodily adjustment, and means actuated by said 10 bodily movement for rotating the tubular member in the casing.
12. A writing pencil comprising an outer tubular casing, an inner tubular member mounted both for rotation and bodily movement in the 15 casing, a longitudinally channelled stem mounted

for rotation within said tubular member but fixed longitudinally in the latter, said stem having a portion projecting from an end of the said member and from the casing and being adapted for reception of a marking element, means operative by relative rotation of the stem and tubular member for feeding said element longitudinally in the stem, means for immobilizing the said member in the casing to permit said relative rotation, means for resiliently retaining the tubular member in a 10 normal position of bodily adjustment, and means actuated by said bodily movement for rotating the tubular member and said stem as a unit within the casing.

HAROLD H. BELCHER. 15
